UNITED STATES PATENT OFFICE.

JOSEPH P. FREDRICK, OF CHICAGO, ILLINOIS, ASSIGNOR OF ONE-HALF TO AUGUST J. LURIE, OF CHICAGO, ILLINOIS.

DOOR LOCK.

Application filed July 31, 1925. Serial No. 47,231.

My invention relates to locks, and more particularly to locks for double doors such as are customarily used in garages wherein the doors are locked at the top and at the bottom of their juxtaposed vertical edges.

The present application is an improvement upon the subject matter of my prior Patent No. 1,534,584 issued April 21, 1925. This prior patent, and the present application, are both concerned with the provision of an easily and quickly opened fastening means for the door, such that a single key may be inserted in a conveniently located lock, the turning of the key releasing the door latches at the top and bottom of the door.

Some of the objects of the present invention are: to provide a simplified form of latch mechanism; to provide an improved construction of housing for this latch operating mechanism; to provide an extensive range of adjustment of both the latch operating rods and of the locking shoulders that the latches engage; to provide latches which will always be supported in proper position to re-engage these shoulders when the door is open; and to provide a self-aligning construction of rotary element for connecting the lock mechanism to the latch actuating mechanism.

These and further objects and features of my invention are set forth in the following description of a specific embodiment thereof. In the accompanying drawings which illustrate such an embodiment:

Figure 1 is an elevational view of the interior side of a double door of a garage provided with the lock of my invention.

Figure 2 is a transverse sectional view through the door illustrating the present lock mechanism in side elevation.

Figure 3 is a longitudinal sectional view through the housing and latch mechanism on a plane parallel to the door.

Figure 4 is a similar view on a plane at right angles thereto.

Figure 5 is a perspective view showing the two halves of the housing.

Figure 6 is a horizontal sectional view taken approximately on the plane of the line 6-6 of Figure 4.

Figure 7 is an upper plan view of the upper latch and its associated locking shoulder,

this view being taken approximately on the plane of the line 7-7 of Figure 8.

Figure 8 is a vertical sectional view taken approximately on the plane of the line 8-8 of Figure 7, and

Figure 9 is a vertical sectional view through the latch at the lower end of the door.

The double door here shown comprises doors 12 and 13, hinged at their opposite vertical edges to the door frame, the free edge of the door 13 preferably being provided with a strip 14 for over-lying the adjacent edge of the door 12, so that the door 13, when locked, will prevent opening of the door 12.

The present locking means comprises an upper latching device 16 for the upper edge of the door, a lower latching device 17 for the lower edge of the door and lock released operating mechanism 18 mounted at an intermediate point on the door 13 and operatively connected to said upper and lower latching devices.

The upper latching device comprises a latch 21 pivoted to a bracket 22 secured by screws 23 to the door 13 (Figures 7 and 8). The latch is pivoted on a pin 24 extending between two ears 25 projecting from the bracket 22. The hook end 21' of the latch is adapted to engage over the dropped intermediate portion 26' of a stationary latch bracket 26. This bracket has relatively wide attaching ears 27 which are slotted at 28 to receive the fastening screws 29. The slots 28 permit inward and outward adjustment of the bracket 26 so that the latch 21 will drop over the locking shoulder 26' when the door is completely closed. This bracket can be easily constructed in the form of a stamping of relatively heavy sheet metal.

When the door 13 is open it is desirable that the latch 21 be supported in proper horizontal position, whereby its curved front end 31 can cam itself over the dropped shoulder portion 26' as the door is swung to closed position. The support of the latch in this proper horizontal position is obtained by extending a tail 32 back from the pivotal center of the latch for engaging the underside of a lug or shoulder 33 on the bracket 22, thereby preventing the latch

from dropping down to a point where its sloping end 31 would not engage the front edge of the latching shoulder 26'. The shoulder 34 on the latch 21 is also adapted to strike this stationary lug 33 on the bracket to prevent the latch from being thrown too high where it might strike the upper door jamb or rail in the closing movement of the door.

16 Extending from the bottom of the latch are two spaced ears 35 between which is pivoted the flattened end 36 of an operating rod 37. This operating rod extends down to the lock released operating mechanism 18, which 15 I shall presently describe.

17 The lower latching device 17 comprises a somewhat similar latch 41 which is pivoted between ears 42 projecting from a bracket 43, secured to the door 13 by screws 44. The 20 hook end 41' of this latch engages over the upwardly turned flange 45 constituting part of a latching floor plate 46. This floor plate also has transverse slots 47 therein for the cap screws 48, these slots permitting inward 25 and outward adjustment of this floor plate similar to the adjustment of the upper bracket 26.

18 This latch also has a tail portion 49 adapted to engage the underside of a stop shoulder 50 formed as a part of the bracket 43. This tail portion striking this stop shoulder prevents the latch from dropping down below a position where its curved front end 51 will cam itself over the locking shoulder 45; and the co-operating shoulder 52, directly above this tail portion 49 also prevents the latch from being thrown up too high. Extending upwardly from the top of 30 this latch are two spaced ears 53 between which is pivotally connected the flattened end 54 of an operating rod 55 which extends up to the latch operating mechanism 18.

19 Attention is directed to the fact that the 45 weight of each latch is effective to drop that latch to an engaging position, and that the weight of both latches is supplemented by the weight of the two operating rods 37 and 55, both of which move downwardly when 50 the latches drop into latching position.

20 The lock released operating mechanism 18 comprises a housing 57 which is affixed to the inner side of the door 13 at a convenient height for the insertion of the key. The 55 present locking device is operated entirely through the instrumentality of the key 58, the insertion of this key, unlocking the lock mechanism and the rotation thereof, lifting the latches to unlock the door. This key is 60 effective to rotate any rotary element comprising part of a suitable lock. The conventional pin-tumbler type of lock is preferable for the present use and accordingly I have shown such a lock at 59, inserted in a bore 65 61, which is drilled through the door 13

and opens into the rear housing 57. A facing disc 62 engages the flange 63 on the lock barrel 59 and bears against the outer face of the door for covering and protecting the outer part of the lock barrel around the 70 edges of the bore 61.

21 The housing 57 comprises front and rear walls or sections 65 and 66, preferably constructed of sheet metal stampings. The front wall 65 has a circular depressed area 67 which is drawn into the rear end of the bore 61 in the mounting of the housing. Two diametrically opposite apertures 68 in this depressed portion 67 receive long screws 69, Figure 6, which thread into tapped holes in the rear end of the lock body 59. By drawing up on these screws, the lock 59 and the housing 57 are drawn into firm engagement with the door 13 and the body portion of the lock is also held against rotation in the bore 61.

22 The rotatable plug portion 71 of the lock preferably has its rear end slotted as indicated at 72, and in this slotted end is pivoted the tongued end 73' of a rotatable shank 73. This shank is of substantially square cross section and is threaded over a considerable portion of its length, the thread being cut in the corners of the square section. This rotatable shank passes through a hole 74 in the depressed portion 67 of the front housing plate, and is extended through this housing and out through an opening 75 in the rear housing plate 66. The pivotal connection and the slight lateral play of the tongued end 73' of the shank in the slot 72 afford a limited universal joint movement and avoid the necessity of accurate alignment of the shank 73 with reference to the lock 59 and the apertures 74 and 75 in the 105 housing.

23 The rotation of this shank 73 is effective to actuate a follower or guide bar 76 to which the upper and lower rods 37 and 55 are connected. This bar is guided in slot like openings 77 in the upper and lower walls of the housing 57. The ends of the bar are turned laterally away from the door and have threaded bosses 78-78 formed thereon for receiving threaded ends of the rods 37 and 55. This bar carries a roller 79 rotatably mounted on a pivot pin 81 secured in the bar.

24 Directly below this pivot pin, the bar has a longitudinally extending slot 82 formed therein through which passes the shank 73. Mounted on the shank 73 on the rear side of the bar 76 is an eccentric 83 consisting of a circular disc or roller having an eccentric located bore therein. A hub 84 is rigidly driven into this eccentric bore. This hub has a neck portion extending through the slot 82 and has an end flange 85 bearing against the front face of the bar 76 along the margins of the slot. This makes the bar and the eccentric 83 a self-contained unit.

The hub 84 has a bore of square section at one end, snugly to receive the shank 73, the other end being of slightly enlarged cylindrical section to facilitate passing the shank 5 therethrough. Two nuts 87 screw over the end of the shank and bear against the eccentric 83, thereby preventing the lock 59 from being pulled out of the end of the bore 61.

The two plates which form the housing 57 10 are stamped out substantially as shown in Figure 5. The front plate 65 has end flanges 88 which form the top and bottom walls of the housing. Each of these end flanges has its center portion notched out as clearly 15 shown in this figure. The other plate 66 has end tongues 89 which take into the cut-out portions of the flanges 88 to a depth sufficient to leave the slots 77 through which passes the actuating guide bar 76. This latter plate 66 has side flanges 91 which form the side walls of the housing. Projecting laterally from the edges of these side flanges 91 are apertured ears 92 which are adapted to align with corresponding ears or lugs 93 20 projecting from the other housing plate 65. Screws 94 pass through these aligned pairs of ears and rigidly fasten the housing to the door. The front housing plate 65 may have an additional pair of apertures 95 for receiving screws 96 adapted to anchor the front plate to the door before the assembly of the housing.

One or both of the operating rods 37 and 55 may be jointed into two sections, such as 35 by the provision of an internally threaded socket 97 on one of the sections receiving the threaded end of the other section, as shown in Figure 2. The ends of the rods which screw into the bosses 78 on the actuating bar 40 76 may be threaded over considerable portions of their length to afford a considerable range of linear adjustment of these rods, the excess portion of each rod projecting beyond the hub 78 after adjustment of the device 45 being cut off. The screw threaded adjustment of these rods in the hubs 78 is, of course, made before the tongued ends 36 and 54 of these rods are finally connected to their respective latches.

50 In the operation of the device, it will be apparent that rotation of the key 58 from the position shown in Figure 4 will revolve the rotatable element 73 and eccentric 83, which eccentric, acting through the roller 79 55 will raise the actuating bar and associated rods and latches. When the key is revolved back to its normal position the eccentric 83 is swung down to the position illustrated in Figures 3 and 4, and concurrently therewith 60 the actuating bar and its associated rods and latches move down under their own weight to bring the latches into locking position. The lock is preferably so designed that the key 58 cannot be removed until the eccentric 65 83 has been rotated down to a position where

the latches can perform their locking function. If the key should be removed while the door is open, the latches will nevertheless be held in proper position for automatically re-latching when the door is pushed shut. 70

Having thus described my invention what I claim as new and desire to secure by Letters Patent of the United States is:

1. In locking mechanism of the class described, the combination of upper and lower locking devices for the upper and lower edges of the door, a housing secured to the rear side of said door, a bar reciprocably supported in said housing and extending above and below the same, rods connecting 80 said bar to said locking devices, a roller pivoted on said bar, said bar having a slot therein, a lock released rotary element extending through said slot, and eccentric means on said rotary element for engaging 85 said roller.

2. In locking mechanism of the class described, the combination of upper and lower locking devices for the upper and lower edges of the door, a reciprocable actuating 90 bar, means for guiding said bar, means connecting said bar to said locking devices, a roller on said bar, said bar having a slot therein, a rotary element extending through said slot, and an eccentric on said rotary element for engaging said roller. 95

3. In locking mechanism of the class described, the combination of upper and lower locking devices for the upper and lower edges of the door, a reciprocable actuating 100 bar having a thrusting surface operatively connected to said locking devices, said bar having an opening therein, a rotary element in said opening, and means actuated by said rotary element adapted to engage a thrusting surface on said bar for reciprocating the latter.

4. In locking mechanism for garage doors or the like, the combination of upper and lower latches, pivot brackets secured to the upper and lower edges of the door on which said latches are pivoted, stationary locking shoulders adapted for engagement by said latches, a vertical reciprocable actuating bar having threaded hubs at its ends, rods screwing into said hubs and pivotally connected to said latches, means for guiding said actuating bar, and lock released means for reciprocating said bar. 110

5. In locking mechanism for garage doors and the like, the combination of pivot brackets secured to the upper and lower edges of the door, upper and lower latches pivotally supported on said brackets, a reciprocable actuating bar, rods adjustably connected at their ends to said actuating bar and pivotally connected to said latches, a housing comprising front and rear sections, flanges on each of said sections forming walls for the housing, the end flanges being spaced to 120 125 130 135

provide guide slots for said actuating bar, said housing being secured to the rear side of the garage door, a cylinder lock mounted in a bore in said door, said bore extending through said door to said housing, screws passing through apertures in the front housing section and engaging holes in said lock, a shank pivotally connected to the rotatable cylinder of said lock and extending through bearing apertures in the front and rear housing sections, an eccentric on said shank, and a roller pivotally mounted on said actuating bar adapted to be engaged by said eccentric.

6. In locking mechanism of the class described, the combination of upper and lower locking devices for the upper and lower edges of the door, lock released operating mechanism connected to said locking devices, and a housing for enclosing a portion of said operating mechanism, said housing comprising a front housing plate and a rear housing plate, said front housing plate having upper and lower flanges having their central portions cut away, said rear housing plate having side flanges and having end tongues extending into the cut away portions of the end flanges of said front housing plate, there being formed guide slots between said

tongues and the bottoms of said cut away portions for guiding the reciprocable actuating bar of said lock released operating mechanism.

7. In a device of the class described, the combination of upper and lower latches for the top and base of a door, means connecting said latches for simultaneous operation, adjustable fixed locking shoulders for said latches comprising a stamped sheet metal U-bracket with out-turned feet and a stamped sheet metal L-bracket and stop means to hold one of said latches in camming relation to enter said U-bracket.

8. In a device of the class described, the combination of reciprocating latch operating means, actuating mechanism for said means, a casing for said actuating mechanism comprising complementary parts adapted to enclose said mechanism and provide guides for said reciprocating means, a closure having a bore, and a stamped depression in said casing to co-operate with holding means to align said casing with said bore.

In witness whereof, I hereunto subscribe my name this 22nd day of July, 1924.

JOSEPH P. FREDRICK.
